ELGIN STODDARD, OF SAN FRANCISCO, CALIFORNIA.

MEANS FOR DISPLAYING AUTOMOBILE-NUMBERS.

1,071,821.

Specification of Letters Patent.

Patented Sept. 2, 1913.

Application filed June 5, 1912. Serial No. 701,742.

To all whom it may concern:

Be it known that I, ELGIN STODDARD, a citizen of the United States, residing at San Francisco, in the county of San Francisco and State of California, have invented 5 new and useful Improvements in Means for Displaying Automobile-Numbers, of which the following is a specification.

The present invention relates to improved 10 means for displaying the license numbers of automobiles.

To discourage reckless and too rapid driving of automobiles it is of great importance 15 that a by-stander should be able to observe with certainty the license number of the automobile, after the machine has passed him, so that he can therefrom ascertain the owner of the machine and the person responsible for such reckless or rapid driving. The means at present provided, so 20 far as I am aware, for affording this information at night are imperfect, because, in the first place, the registry numbers are displayed too obscurely, and, secondly, said 25 numbers are arranged at right angles to the direction of travel of the machine, so that, even if otherwise distinct, they cannot be clearly seen until the machine had progressed a considerable distance past the 30 observer, and then they are generally too remote to be easily legible.

One object of the present invention is to 35 provide means for displaying the license number which will be free from these defects.

A further object of the invention is to 40 provide means whereby an observer ahead of the machine may be apprised whether or not the machine has its tail lamp lighted 45 and its license number at the rear of the machine illuminated.

In the accompanying drawing, Figure 1 is a broken plan view of an automobile equipped with my invention; Fig. 2 is a similar view showing a modification of the 45 invention.

Referring to the drawing, 1 indicates an automobile, on one side of which, and to the rear above the mud guard, is secured a casing 2, in the front end of which is a lamp 3, a forwardly directed lens 4 being secured in front of the lamp 3. Said casing has an oblique side 5 which supports rearwardly and outwardly facing numerals 6 in position to be directly illuminated by rear- 55 wardly radiating rays from said lamp.

7 indicates a tail lamp also carried by said casing. This tail lamp may be omitted, as in the modification illustrated in Fig. 2, in which the numerals are placed on an out- 60 wardly and rearwardly facing plate 8, and are illuminated by rays of the lamp 3 re- flected from a reflector 9.

I claim:—

In combination, a casing, a lamp, near 65 one end thereof, said casing being provided with means arranged to permit the passage of rays radiating forwardly from the lamp, and having a laterally extending portion 70 formed to support rearwardly and out- wardly facing numerals in position to be directly illuminated by rearwardly radiating rays from said lamp.

In testimony whereof I have hereunto 75 set my hand in the presence of two subscri- ing witnesses.

ELGIN STODDARD.
